 International Business Machines Corporation,
 New York, N. Y., a corporation of New York

Application December 1, 1936, Serial No. 113,590

19 Claims. (CL. 101—96)

This invention relates to improvements in printing mechanisms and more particularly to the type adapted for high speed printing operations.

5 Printing mechanisms of the reciprocating type employing type striking hammers have been provided for calculating machines of the key and card controlled types but such forms are objectionable due to the shocks imparted to the 10 mechanisms by operating mechanisms of the reciprocating type. Such forms of printing mechanisms by reason of their reciprocating movements are not capable of the extremely high speed printing operations desired and are further objectionable in that they are noisy in 15 operation.

Another form of printing mechanism comprises printing wheels, usually of the gear type and printing from a gang of type wheels has proposed to be accomplished by forcing them against 20 a platen. Where a gang of such wheels is employed in a number of about sixty to eighty in tabulating machines the type wheels are carried by shafts in sub-groups for evenness of printing. 25 For further securing even printing operations it has been proposed to carry each type wheel by an individual member whereby the unevenness of a platen or surrounding paper strip can be overcome.

30 However desirable are the characteristics that may be derived by the last mentioned constructions of printing mechanisms they do not permit the possibility of securing many carbon copies and for such operations a hammer blow is necessary and which cannot be secured by merely forcing the type against a resilient platen.

The present invention has for its main object the construction of a printing mechanism which will permit the use of type wheels and effect 40 printing by utilizing the type wheels themselves as hammers so as to secure legible printing with one or more clear carbon copies.

This object is attained by first differentially setting the type gear by an operating gear and 45 after such setting cause resilient means to be effective to roll the type gear wheel over the operating gear until the selected type strikes the platen and in the nature of a hammer blow.

Another object of the invention is to devise a 50 construction to mount each wheel individually for independent rocking motion so that the resulting imprint will have even impression characteristics.

A still further object of the invention is to 55 devise a construction of resilient means to cause

the type wheel to strike the platen with a hammer blow and then by the resilient means be immediately shifted away from the platen with such timing as will prevent rebound of the type wheel and cause over-printing.

A still further object of the invention is to devise a construction of resilient means to cause a hammer blow by the type wheel that will operate in the nature of a toggle.

Another object of the invention is to incorporate aligning means for the operating gears so that the latter are aligned and locked prior to the rolling of the type gear wheels over the operating gears, insuring that the selected type will squarely strike the platen and thus preventing 15 "shadow" printing.

Another object of the invention is to incorporate in the novel printing mechanism a means for eliminating the printing of unnecessary zeros and to cause the insertion of zeros in orders lower 20 than the order in which the highest denominational digit is printed.

A still further object of the invention is to devise a construction whereby the novel printing mechanism may be split or sub-divided into separate sub-sets.

Other objects which are relatively important but which are far too numerous to be mentioned herein will be obvious as the specification is understood and all of which are attained in an 30 efficient manner in construction and design and produce a printing mechanism for a tabulating or other machine having very desirable characteristics in performance, operation and simplicity in construction and manufacture, servicing and 35 appeal in commercial requirements.

The printing mechanism is of a type which can be applied to machines of forms other than a tabulating machine in which it is shown as an 40 illustrative embodiment.

In said drawings:

Fig. 1 is a diagrammatic view of certain essential elements of a tabulating machine for controlling the setting of the printing elements of the printing mechanism,

Fig. 2 is a sectional view showing the improved construction of printing mechanism and the main drive therefor,

Fig. 3 is a detail of the clutch mechanism,

Fig. 4 is a detail view of a modification showing a preferred means for adjusting the tension of certain springs used to effect the printing impressions.

The machine in which the present improvements have been incorporated is well known and 55

is exemplified in the patents to Lake No. 1,379,268, dated May 24, 1921; No. 1,600,413, dated September 21, 1926; and the patent to Daly et al., No. 1,896,540, dated February 7, 1933.

5 In machines illustrated in detail in the above described patents and generally herein, tabulating cards 10 (Fig. 1) are adapted to be fed singly by a picker 11 from a supply stack to a pair of upper feeding rollers 12 which convey the card so 10 as to have the perforations of the card analyzed by the usual perforation analyzing brushes 13 while the card is in motion. The card analyzed then passes to a lower set of feeding rollers 14 which then convey the card to a storage hopper, 15 usual in the type of machine referred to.

15 Card feeding operations are instituted by the usual manual start key designated as ST in the last mentioned patent so as to cause by an electrical circuit the energization of a card feed 20 clutch magnet 15.

20 The power for driving the card feeding rollers and other parts of the machine is derived from a motor (not shown) which by a belt 16 and pulley 17 constantly rotates a ratchet wheel 19 secured thereto. The pulley 17 and ratchet wheel 19 are loosely mounted upon a shaft 18.

25 In Fig. 1 there is shown the card feed clutch for causing card feed and is similar to the card feed clutch disclosed in Fig. 1a of the Lake Patent No. 1,822,594, dated September 8, 1931, to 30 which reference should be had for further details of construction and operation.

30 Upon completion of the electrical circuit to the clutch magnet 15 the latter attracts its armature 20 to raise a clutch lever 21 to thereby unlatch the latter from a clutch pawl 22. The latter is then drawn by a related spring 23 to engage the constantly rotating ratchet wheel 19. The clutch pawl 22 is carried by a bar 25, which 40 is secured to a disk 26 secured to shaft 18 and to the latter there is secured a pinion 27.

45 The construction and operation of the card feed clutch, as is well known, is such that upon energization of magnet 15 disk 26 will be rotated and successive rotations of the shaft 18, and therefore pinion 27, will ensue as long as tabulating operations are desired.

50 The pinion 27 is in mesh with a gear 28 and the latter drives the upper set of feeding rollers 12 and the lower set of feeding rollers 14. The upper set of feeding rollers is intergeared by pinions 29 one of which is rotatable with a gear 30 in mesh with the driving gear 28. The latter also meshes with a pinion 31 which is rotatable with 55 one of a pair of intergeared pinions 32 carried by the rollers 14 which drive the lower set of feeding rollers 14 in opposite directions. The driving gear 28 is of sufficient width to drive a gear 34 so that by a train of gears 35, 36 a shaft 37 is driven. It is understood that as is usual in tabulating machines the card feed clutch is so designed and the gears are so proportioned that shaft 37 will be given a complete revolution 60 in the arrow direction shown in Fig. 1.

65 It is customary in the type of machine described to cause printing from type of a printing mechanism which are presented to a printing line in a proper relationship with the analyzing of the index points of the card and to 70 carry out the printing function in a novel manner the improved construction will now be described.

Printing mechanism

75 Referring to Fig. 2 there is shown a printing

unit for a single order and which, obviously, is duplicated to effect multiple order printing.

The shaft 37, which, it is recalled, is rotated a single revolution has secured thereto a mutilated gear 38 adapted to drive a mutilated gear 39 secured to a shaft 40. To the shaft 40 there is secured a gear 41 meshing with a pinion 42 secured to a shaft 43 which is adapted to be driven by the gearing just described preferably two and one tenth revolutions for each revolution of the shaft 37, although at times its rotation is interrupted, as will be explained later, to permit certain functions to be performed.

10 To the shaft 43 there is attached, for each denominational order, a ratchet wheel 44 and loosely mounted upon the shaft 43 is a pinion 45 meshing with an operating gear 46. Attached to the pinion 45 is a disk 47 to which is pivoted at 15 48 a clutch dog 49 provided with the usual clutch tooth 50 adapted to be engaged with one of the teeth of the ratchet wheel 44. The clutch tooth 50 is normally held out of engagement with the ratchet teeth by means of a bell crank 51 pivoted on a rod 52. The horizontal arm 53 of said bell crank 51 normally abuts the extremity of the 20 clutch dog 49 to hold the clutch tooth 50 out of engagement with the ratchet wheel 44 and such relationship is maintained against the tension of a normally tensioned spring 54. The vertical arm of the bell crank has a link connection 25 55 to the armature 56 of a printer controlling magnet 57. The magnet 57, as will be subsequently explained, is energized by an electrical impulse transmitted thereto under control of a 30 card perforation at a differential time and coincident with the analysis of the perforation.

35 The magnet 57, as shown in Fig. 1, is in circuit connection with the analyzing brush 13 so that when the latter encounters a perforation the energization of the magnet 57 will cause its armature 56 to be attracted and the link 55 drawn to the right, thereby rocking the bell crank 51 so as to release the clutch dog 49 for movement by its 40 spring 54, thereby causing the clutch tooth 50 to engage with one of the teeth of the ratchet wheel 44 and causing by the shaft 43, which is now rotating synchronously with the passage of the index points past the analyzing brush 13, the rotation of the pinion 45 and the operating gear 46 a number of steps commensurate with the 45 digital value designated and determined by the 50 perforation sensed.

55 For each order there is an operating gear 46 which is loosely mounted upon a fixed support rod 58 and each operating gear 46 is in mesh with a type gear wheel 59, each type gear wheel being loosely mounted on a stud 60 carried by a related arm 61 which is loosely mounted upon the shaft 58. To each of the individual arms 61 there is connected a normally tensioned spring 62 the spring acting to rock the arms 61 clockwise but such action is normally restrained by a bail 63.

65 Each printing gear wheel 59 carries on its teeth raised printing type of all the digits 0-9 inclusive, so that obviously, the differential actuation of the operating gear 46 will rotate the type gear wheel 59 a commensurate amount. The rotation of the shaft 43 equivalent to $1\frac{1}{10}$ revolution is employed to set the wheels differentially 70 and the timing of the card feed is such as to cause electrical impulses to be directed to the magnets 57 after $\frac{1}{10}$ of a revolution of the shaft 43 has been effected. It is also clear from Fig. 75 3 that the ratchet wheel 44 will rotate counter-

clockwise idly through an angle equivalent to one tooth space after an electrical impulse is sent to magnet 57 before the clutch tooth 50 will engage. Obviously, for the setup of a "9" 5 digit the disk 47 will be rotated nine steps during the remainder or nine-tenths of the revolution of the shaft 43. The purpose of this timing is to secure the proper synchronism between card feed and the rotation of the type wheel so that 10 any digit up to nine can be set up prior to stopping the shaft 43.

After the set up of the type by the shaft 43 the concentric surface 64 of the gear 38 will 15 contact with the Geneva lock projection 65 of the gear 39 thereby causing the shafts 40 and 43 to remain idle during the continued rotation of the main drive shaft 37.

Aligning devices

20 Just prior to the time the type gear wheels 59 have been differentially rotated to represent the value designated on the card a profile cam 66 on shaft 37 which coacts with a roller 67 carried by a pitman 68 will permit a spring 69 connected to 25 the pitman to rock the pitman downwardly, since at this time the roller enters the recessed part of the cam 66. The pitman 68 is connected to a rearward extension 70 of one arm 71 which together with another arm similar to arm 71 carries a bail 72. The bail 72 is provided with slots 30 through which pass the operating gears 46.

Pivotedly mounted on a fixed rod 74 is an aligning bar 75 carried by a pair of arms 76 and by means of a rod 77 bent at right angles which is 35 carried by the bar 75 a roller 78 is carried by said bar. A spring 79 attached to one arm 76 of the bar 75 causes the roller 78 to bear against the bail 72. When said bail 72 is elevated the roller 78 will be free of the bail so that the spring 79 urging 40 the bar 75 will permit roller 78 to ride down on inclined projection 73 of the bail to cause the wedge shaped notch 80 of the bar to engage the teeth of the now differentially positioned operating gears 46 thereby aligning them and the type 45 gear wheels 59 in proper differential positions.

Thereafter a cam 81 secured to the shaft 37 will rock a bell crank 82 and since the vertical arm of the bell crank has a hooked connection with the bail 63 by an arm 83 pivoted at 84 to one arm 50 of the bail and hooking over the vertical arm of the bell crank, the cam 81 will rock the bail 63 about its pivot 85. The bail 63 is now withdrawn from locking cooperation with shoulders 86 of the arms 61 permitting springs 62 to rock the 55 arms 61 and in so doing the type gear wheels 59 will roll over the operating gears 46 which are now stationary.

The arms 61 in normal latched position are each so positioned as to effect when unlatched a 60 rolling of the type gear wheel 59 over the operating gear 46 through an angular distance sufficient to cause an impact between a selected type 65 on the type gear wheel and a platen 87. This is effected after the release of the arms 61 by the bail 63, the normal tension in the spring 62 causing the arm 61 to be rocked clockwise about the shaft 58. This tension is effective until the axis of the spring 62 and the centers of the stud 60 and of the shaft 58 are in alignment. At this 70 time the momentum imparted to the arm 61 is sufficient to further rock the arm 61 causing a further rolling of the type gear wheel 59 and during this time the spring 62 will be retensioned so that after the impact between a selected type 75 and the platen the arm 61 will be shifted reversely

by the retensioned spring 62 and about the time the spring 62, stud 60, and shaft 58 are again in alignment by means to be subsequently described the arms 61 are positively returned to relatched position. This will effectively prevent any rebound of the type gear wheels 59 to cause overprinting. The angular relationship between spring 62 and arm 61 causes both to function as a toggle so as to impart considerable momentum to the type gear wheel whereby the type of the latter will strike the platen with a hammer blow, and the relationship shown was found, in practice, to be the best for efficient printing operations.

The numeral type are positioned as shown in Fig. 2 by the numbers adjacent the gear teeth. In the event a zero is to be printed there will be no movement given to the operating gear 46 so that the type gear wheel in rolling over the operating gear 46 will cause the "0" type to print. 15 Each printing type will strike an inking ribbon 88 and force it against the usual paper strip surrounding the platen. If a "1" is to be printed the type gear wheel 59 is rotated counterclockwise one step so that in rolling over the operating gear 46 20 in a clockwise direction the "1" type will effect the printing impression. For printing a "2" the type gear wheel 59 is rotated counterclockwise 25 two steps, and so on for selecting the other type for printing.

30 After the printing action the arms 61 are restored to normal relatched position and in so doing roll the type gear wheels reversely to normal position. Each arm 61 is provided with a finger 89 which is beneath an extension 90 of the 35 bail 72. A plurality of extensions 90 are formed integral with the bail, one for each finger 89 of the arms 61. When the bail is elevated to permit the gears 46 to be aligned the extensions 90 are withdrawn out of cooperation with the fingers 89 40 so that the arms 61 are free to be rocked. When the printing impression has been made the cam 66 will elevate the pitman 68 rocking bail 72 downwardly, and by the inclined portion 73 cooperating with roller 78 the bar 75 will be shifted 45 to the left to normal position. During this operation the extensions 90 in cooperation with the fingers 89 will rock the arms 61, and since in the meantime cam 81 has also turned so that it will permit the bail 63 to be returned to normal by a 50 spring, the latter will relatch the restored arms 61 in normal position as the shoulders 86 pass beneath, in readiness for another printing operation.

Zero elimination and insertion mechanism

55 It is, of course, undesirable to print zeros at the left of the digit of the highest denominational order and in the present construction this is effectively prevented by pivoting on a rod 91 a 60 series of zero printing control arms 92 each of which is urged by a spring to engage a restoring rod 94 carried by the arms 76. Each arm 92 has an extension 95 which carries a feeler 96 and a hook 97. Attached to each operating gear 46 is 65 a plate formed with a series of control notches 98 one of which cooperates with the related feeler 96 in the event that the operating gear 46 is not rotated which occurs if the digit entered is zero. When the aligning bar 75 is moved to the right 70 the rod 94 will permit the control arms 92 to be rocked clockwise by their springs and any feeler 96 which enters a control notch 98 will permit the related extension 95 to be rocked sufficiently 75 to cause the hook 97 to engage a lug 99 of the

associated arm 61, thereby preventing the release of the arms 61 in orders higher than that of those above the highest denominational order of the number printed.

5. However, desirable this may be in the circumstances just explained, it is necessary to fill in zeros for denominational orders which are at the right of a digit which is other than "0" and which is printed. For example, in printing the amount —2.03— it is necessary to cause the arm 61 of the tens denominational order to be released to print zero even though no movement has been given to the related operating gear 46.

In the present machine this is effective by providing coupling levers 100 each of which is pivoted at 101 to said arms 92. Each lever 100 at its extension thereof is provided with a lug 102 and if the related arm 92 is not rocked due to the fact that some digit other than "0" is printed then 15 said lug will engage an extension 103 of the arm 92 of the next lower order. The arm 92 of the next lower order will thereby be held even though the notch 98 cooperates with the related feeler 96. Since the related arm 61 can be released for individual operation it follows that the gear type wheel of lower order will cause the insertion of the "0" digit.

Split control mechanism

30. The printing mechanism may be split so that the successive orders may be sub-divided into a plurality of independent sub-sets and this is accomplished by providing each of the coupling levers 100 with a manually operated portion 104 which is adapted to be rocked so as to prevent the coaction of the lug 102 and the extension 103. This form of split mechanism is well known in the art.

Restoration of type gear wheels to normal position

40. With the present understanding of the operation of the machine, it will be observed that the type gear wheels 59 and operating gears 46 are moved to differential positions if the digit to be printed is other than zero. It will be obvious that after the printing operation the type gear wheels should be returned to normal position and this is effected by a further rotation of the shaft 43 to the extent of $\frac{1}{5}$ of a revolution after it has 45 been temporarily stopped in its rotation during the printing operation.

After the Geneva lock is disabled the gear teeth 105 will cooperate with the gear teeth 106 so as to drive shaft 40 and through the gears 41 and 42 55 further drive the shaft 43 $\frac{1}{5}$ of a revolution. For the entry of a "9", for example, the disk 47 has been rotated counterclockwise through an angle equivalent to nine tooth spaces of gear 45 by the first rotation of the shaft 43 so that, in the example assumed, in order to bring the type gear wheel 59 to normal or "0" position the disk 47 should be given a movement of one step and this step of movement is effected at the beginning of the $\frac{1}{5}$ of a revolution of the shaft 43. At the 60 termination of the one step of movement the arm 53 will be contacted by the clutch pawl 49 (since in the meantime magnet 57 has been deenergized) thereby disengaging the clutch tooth 50 from the ratchet wheel 44 permitting the shaft 43 to idly 65 rotate the remainder of the revolution or seven steps.

Obviously if a "1" has been printed by the adjustment of the related type wheel the shaft 43 during its rotation of eight tenths will turn the 75 type gear wheel 59 eight steps but the ninth step

occurs at the start of the next cycle to bring it to normal position.

Summarizing, during the rotation of the shaft 43 after it has been stopped the type gear wheels 59 are turned complementary amounts to bring them to normal positions.

Adjustment for varying number of carbon copies

The upper end of the spring 62 has connected thereto a spring clip as shown in the modification in Fig. 4 which comprises lateral projections 107 fitting in the convolutions, and a center rod 108 which has a hook 109. Through said hook a rod 110 passes. The rod 110 is carried by bent projections 111 of a plate 112 which is slidably mounted on a bar 114 and fixed in adjusted position by screws 113 passing in the bar 114.

Obviously the spring clips can be rotated more or less so that the initial tension of spring 62 can be selected to cause even impression characteristics. Such adjustment is preferably made in manufacture and for collective adjustment of a series of springs 62 the plate 112 is adjusted for the desired number of carbon copies. By shifting plate 112 upwardly from the position shown, the series of springs 62 is collectively increased in length and tension and at the same time the angle is changed so as to increase the impact between the platen 87 and type gear wheels 59 when more carbon copies are desired. A scale may be provided to indicate the necessary adjustment of the plate 112, as shown in Fig. 2.

While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a printing machine, in combination, a platen, a plurality of type gear wheels in axially aligned position and each mounted for a rolling movement about its axis and a rocking motion about a pivot from the axially aligned position to select a type for printing and to cause the selected type to impact said platen, means for differentially setting said type gear wheels while in axially aligned position, and a single means for each type gear wheel comprising a normally tensioned spring for causing the type gear wheel to roll about its axis and during such movement rock about its pivot from its axially aligned position to cause the selected type to impact said platen.

2. In a printing machine, in combination, a platen, a plurality of type coaxially aligned gear wheels mounted for rocking motion about a pivot, means meshing with said type gear wheels for differentially setting said type gear wheels while the latter are in aligned position and mounted upon said pivot, and a single means one for each type gear wheel for causing said type gear wheel to roll about its axis from its axially aligned position over said setting means and to effect a rocking motion to impact said platen.

3. In a printing mechanism for a machine for listing data, in combination, a series of type printing cylinders, a pivoted arm for carrying each cylinder, means mounted on the pivot of said arm for setting said type cylinders to select predetermined type, a platen, means comprising a ball engaging each of said arms for holding said

- type printing cylinders while they are being set and against the action of springs which are independently operable to individually rock said arms to impact said cylinders against said platen, 5 means in said machine for releasing said bail at a predetermined time in the machine operation to cause the simultaneous movement of said type cylinders by said springs to independently impact said platen, and means for locking said setting means against movement to cause each cylinder to roll about its axis when the type cylinders are released to impact said platen.
4. In a machine of the class described, in combination, a plurality of operating gears, means 10 for causing the setting of the operating gears differentially to rest positions, a plurality of gear type wheels meshing with said operating gears and rotated thereby during the setting of the latter to select type thereon, means for mounting 15 each of said gear type wheels to roll about its axis, a platen, and resilient means effective after the operating gears are at rest positions for causing the gear type wheels to roll about their axes to impact said platen with a hammer blow.
- 20 5. In a machine of the class described, in combination, a plurality of operating gears, driving means for said gears, means for causing the driving means to set said gears to differential positions, a plurality of gear type wheels meshing with the operating gears and rotated thereby during the setting of the latter for selecting type on said gear type wheels, means for mounting said gear type wheels to roll over said operating gears, a platen, normally ineffective resilient 25 means for causing the gear type wheels to roll over said operating gears to impact said platen, and means operated by said driving means for causing the resilient means to be effective.
6. In a machine of the class described, in combination, a platen, operating gears, gear type wheels meshing with the operating gears, means for setting said operating gears to rotate the gear type wheels to differential positions, means for mounting said gear type wheels to roll over said operating gears, normally ineffective resilient 30 means for causing the gear type wheels to roll over said operating gears to impact said platen, means for restraining the action of said resilient means, and means for disabling said restraining means at a predetermined time in the operation of the machine.
- 35 7. In a machine of the class described, in combination, a plurality of operating gears, a plurality of type gear wheels, individual means for mounting said type gear wheels for rolling the type gear wheels over the operating gears, a platen, normally ineffective resilient means for individually causing the type gear wheels to roll over the operating gears to propel the type gear 40 wheels against the platen, means comprising a bail engaging said mounting means for restraining the action of said resilient means, and means for operating said bail to cause said resilient means to be effective.
- 45 8. In a machine of the class described, an operating gear, a gear type wheel mounted for a rolling movement over the operating gear, means for setting the operating gear differentially to select a predetermined type by an initial 45 rotation of the type gear wheel, a platen, and means for causing said type gear wheel to roll over the operating gear to supplementally rotate the type gear wheel to cause the selected type to impact said platen.
- 50 9. In a machine of the class described, in combination, operating gears, a plurality of gear type wheels mounted to roll over said operating gears, means including said operating gears to initially rotate the gear type wheels forwardly to differential positions to select type, a platen, and means for causing the gear type wheels to roll over said gears after their initial rotation to cause the selected type to impact said platen.
- 55 10. In a machine of the class described, in combination, a plurality of gear type wheels, arms for carrying said wheels, means for initially rotating said wheels to differential positions to select predetermined type, a platen, resilient means for causing said gear type wheels to roll about their axes to impact said platen, a bail cooperating with said arms, and means for moving said bail to position to release said arms for action by said resilient means at a predetermined time in the operation of the machine.
- 60 11. In a machine of the class described, in combination, a type gear wheel provided with type which are selected for printing, a platen, a pivoted arm for mounting said type gear wheel, a normally tensioned spring connected at one end to said arm, anchoring means for securing the other end of said spring to provide by the location of said anchoring means a normal angular relationship between the axis of said spring and said arm so that as the normal tension is released it causes the rocking of said arm to cause the type 65 gear wheel to be moved towards said platen, said spring thereafter being retensioned by said arm as the momentum imparted to said type gear wheel causes it to be further moved to impact said platen, and means for reversely rocking said arms to thereby cause the normal tension in said springs.
- 70 12. In a machine of the class described, in combination, a platen, an operating gear, a type gear wheel, means comprising an arm for mounting said type gear wheel to roll over said operating gear, means for causing said operating gear to rotate said type gear wheel to select a type, and a normally tensioned spring connected to the arm, anchoring means for securing the other end of the spring to provide by the location of said anchoring means a normal angular relationship between the axis of said spring and said arm so that as the normal tension of the spring is relaxed it causes the rocking of said arm to cause the related type gear wheel to roll over the operating gear, said spring being then re-tensioned by said arm as the momentum imparted to the rolling type gear wheel causes it to impact said platen.
- 75 13. In a printing machine, in combination, a platen, a plurality of type printing elements, a revoluble shaft revolving in the same direction two rotations for each machine operation, setting and restoring means for said type printing elements including said shaft and operable thereby during the first rotation of said shaft for setting said type printing elements and during the second rotation to restore said type printing elements to normal, means for causing said type 80 printing elements to impact said platen, and means for causing the interruption of the first rotation of said shaft while the last named means is operating.
- 85 14. In a printing machine, in combination, a plurality of type printing elements, a revoluble shaft revolving in the same direction two rotations for each machine operation, setting and restoring means for said type printing elements including said shaft and operable thereby during the first rotation of said shaft for setting said type printing elements and during the second rotation to restore said type printing elements to normal, means for causing said type printing elements to impact said platen, and means for causing the interruption of the first rotation of said shaft while the last named means is operating.

- ing the first time said shaft is rotated for setting said type printing elements, and during its second rotation restore said type printing elements to normal, a platen, means for causing independent 5
6 rocking motion of said type printing elements about a pivot to impact said platen, and means comprising a Geneva drive for causing the interruption of the first rotation of said shaft while the last named means is operating.
- 10 15. In a printing machine, in combination, a platen, card analyzing means, a plurality of type printing elements, a revoluble shaft revolving at two different times for each machine operation, means including said shaft and under control of 15
15 said analyzing means for setting said type printing elements during the first time said shaft is rotating, means for causing said type printing elements to effect a rocking motion about a pivot to impact said platen, and means for causing the interruption of rotation of the shaft during 20
20 the operation of the last-named means, said shaft thereafter during its second rotation restoring the type printing elements to normal.
16. In a printing machine, in combination, a platen, a plurality of type wheels mounted for a 25
25 rocking motion about a pivot to impact said platen, individual springs normally tensioned for causing said rocking motion of said type wheels, means for individually adjusting the tension of 30
30 said springs, and means for collectively varying the tension of said springs to vary the impact between said platen and type wheels.
17. In a machine of the class described, in combination, a type gear wheel, means comprising a 35
35 rockable arm for carrying said type wheel, a normally tensioned spring connected to said arm, anchoring means for securing the other end of the spring to provide by the location of said anchoring means a normal angular relationship

between the axis of said spring and said arm so that the rocking of the arm in one direction relaxes the tension of said spring and then the further rocking of said arm in the same direction retensions the spring, and means for reversely 5
5 rocking said arm to cause the normal tension in said springs.

18. In combination, a platen, an arm, a type gear wheel mounted on said arm for a rocking motion about a pivot of said arm to impact said 10
10 platen, a setting gear meshing with the type gear wheel for initially rotating said type wheel gear and mounted on said pivot, a normal tensioned spring connected to said arm, anchoring means for securing the other end of the spring to provide by the location of said anchoring means a 15
15 normal angular relationship between the axis of said spring and said arm so as to cause both a rolling movement of the type gear wheel about its axis over the setting gear subsequent to its 20
20 initial rotation, and the rocking motion of the arm to cause said type gear wheel to impact said platen, and means for reversely rocking said arm to cause the initial tension in said spring.

19. In a machine of the class described, the 25
25 combination with a plurality of numeral type wheels, of means for analyzing a perforated record, means controlled by said analyzing means for effecting an initial rotation of said type wheels synchronously with the analysis of the perforations to select certain numeral type but not to 30
30 present desired numeral type to a printing line, and means for causing a supplemental rotation of said type wheels to present desired numeral type which are representative of the numeral representing perforations analyzed to said printing line.

FREDERICK L. FULLER.
